NOVEL 17-KETALS OF 1-SUBSTITUTED-4-ALKYLATED ESTRA-1,3,5(10)-TRIENES

AYED ESTRA-3,545,462) PAPER
Leland L. Smith, Malvern, Pa., assignor to American
Home Products Corporation, New York, N.Y., a cor-
poration of Delaware
No Drawing. Filed Aug. 24, 1962, Ser. No. 219,129
11 Claims. (Cl. 260—239.5)

This invention relates in general to a novel series of 17-ketals of 1,4-substituted estra-1,3,5(10)-triene, methods of preparing the same, intermediates and pharmaceutical compositions containing these novel compounds.

The compounds of the invention may be more particularly described by reference to the general formula:

wherein R represents a substituent selected from the group consisting of hydrogen, lower alkyl, lower alkenyl, lower cycloalkyl, lower aralkyl, and acyl; R' represents lower alkyl; and W represents a member selected from the group consisting of alkylenedioxymethylene, alkylene-thioxymethylene and alkyleneedithiomethylene.

In the above definition the term lower alkyl as employed herein refers to those alkyl groups having from about 1 to 20 carbon atoms, and more particularly to those having less than about 10 carbon atoms. The alkyl group may be normal or branched in structure although the normal chain is generally preferred. Some examples of these alkyl groups would be methyl, ethyl, propyl, butyl, isopropyl, isobutyl, pentyl, octyl, dodecyl and cetyl to name a few of such substituents. The term lower cycloalkyl refers to that substituent wherein the carbon atoms are joined in a carbocyclic ring which is generally a 5 or 6 membered ring but which may contain a smaller or larger number of carbon atoms subject to the practical limits of stability of such structures. Cyclohexane would be an example of a preferred member of this class of substituents. The term lower aralkyl refers in general to an alkyl group of from about 1 to 20 carbon atoms substituted by an aromatic ring structure. An instance of this type of substituent would be benzyl, phenylethyl, phenylisopropyl, and the like. By the term lower alkenyl as it is employed herein, it is intended to refer to those unsaturated hydrocarbon radicals containing at least one double bond in the chain such as allyl, vinyl, and the like. In the present usage this term embraces all such radicals having less than about 20 carbon atoms and preferably less than about 10 carbon atoms.

An essential portion of our novel structure is the substitution indicated by W in the 17-position of the steroid molecule. It is intended by the definition of alkylenedioxymethylene as employed to define W that it embrace such ketals containing up to about 10 carbon atoms but preferably not more than about 4 carbon atoms. By the term alkylenthioxymethylene it is intended to include those ketals where one oxygen atom of the structure has been replaced by a sulfur atom. In a corresponding manner the term alkylenedithiomethylene as it is employed herein refers to those ketals wherein both oxygen atoms have been replaced by a sulfur atom.

2

The novel compounds of the invention may be prepared by means of the following general method:

The known starting material 1-hydroxy-4-methylestra-1,3,5(10)-trien-17-one (I) may be ketalized with a suitable ketalizing agent such as ethylene glycol (or other alkylene glycol, as 1,3-propanediol, etc.) in a solvent such as benzene with a condensing agent such as p-toluenesulfonic acid at temperatures up to the reflux temperature of the solvent employed for from about 2 to 24 hours' duration in such a manner as to produce the 17-ethylene ketal (II), which in turn may serve to lead to the 1-ethers, represented in the above diagram as the 1-methyl ether (III), by etherification such as by the action of dimethyl sulfate and alkali on the 1-phenol (II). Other 1-alkyl ethers can be prepared by use of other alkylating agents as described in the examples herein appended. As an alternative procedure to esterify, the 1-phenol (II) may be acylated with a suitable acylating agent, such as acetic anhydride in pyridine, to form the 1-acetoxy ketal (IV). Other acylating agents such as propionic anhydride, benzoyl chloride, etc. in pyridine may be used to afford the respective 1-esters.

In the preparation of the 17-ketals of this invention as illustrated above only one of a plurality of possible methods of ketalization has been disclosed. It should be understood that within the general framework of the invention other alternative means of ketal formation may be employed if desired. For instance the process of 17-ketalization to form these novel compounds may be carried out by an exchange reaction which is known as exchange ketalization. In this method the 17-ketone to be ketalized is contacted with the ketal of another carbonyl compound such as the ethylene ketal of acetone, methyl-ethylketone, mesityl oxide or the like in the presence of an acidic catalyst to effect a transfer of the ketal function from the latter compound to the former one. This reaction may be conducted either in the presence or absence of heating as specific conditions dictate. In any event one is thus able to obtain the 17-ketals of the invention.

65 It should further be noted that the present invention
also comprehends the preparation of so-called "open
chain" 17-ketals wherein the carbon atoms attached to
the oxygen or sulfur atoms are not in fact joined together.
70 However the preparation of compounds such as these will
become clear to those skilled in the art after consideration
of the foregoing disclosure.

The compounds of the invention are useful in the field

of experimental pharmacology as well as being valuable intermediates for further steroid synthesis in preparing new steroid compounds. In addition, many of the compounds of the invention have been found to demonstrate high antilipemic properties coupled with low feminizing action. Also, besides having capacity to regulate blood lipids, the compounds are useful for their general hormonal effect, particularly in the female. Therefore many of the compounds would be expected to exhibit utility in those areas where estrogens are employed, such as female hypogonadism, amenorrhea, dysmenorrhea metrorrhagia, ovulation block and contraception, pregnancy maintenance, arteriosclerosis, osteoporosis, menopausal symptoms, infertility, regulation of water balance, functional uterine bleeding, and the like.

The novel compounds of the invention when contemplated for use in pharmaceutical products, may be admixed and administered in combination if desired with a large number of compatible diluents, carriers and the like to form a pharmaceutical composition. Such well-known liquid carriers as mineral or vegetable oil or a lower aliphatic alcohol may be used where injectables are to be prepared. Glycerine or the like may be used where the compound is to be administered as a syrup. Solid excipients, binders, extenders or carriers such as carboxymethylcellulose, starches, sugars and the like may be added where tablets or powders are to be employed as a means of administration. The dosage of the compounds will vary with the severity of the ailment and in general can vary from about 0.5 to 100 mg./kilo of body weight per day depending upon the many factors of the case involved.

While the foregoing flow diagrams generally illustrate a means of obtaining the various compounds of the invention, there is no doubt that others will be brought to mind. It is applicant's intention to claim all of these structures. The following examples serve only to illustrate the method of preparing some specific compounds of this series. It is to be understood that for a proper legal definition of the invention, attention must be directed only to the several appended claims.

EXAMPLE 1

17,17-Ethylenedioxy-4-Methylestra-1,3,5(10)-Trien-1-Ol

Reflux a mixture of 485 mg. of 1-hydroxy-4-methylestra-1,3,5(10)-trien-17-one, 85 mg. of p-toluenesulfonic acid, 50 ml. of benzene, and 5 ml. of ethylene glycol with removal of water via a Dean-Stark apparatus for 20 hours. Wash the cooled mixture with saturated potassium bicarbonate solution, with water, and finally dry over anhydrous magnesium sulfate. The evaporated benzene solution will yield 550 mg. of solids, M.P. 234-235°, lacking in absorption near 5.85 μ . Recrystallization of the solids from ethyl acetate will give the pure product, M.P. 240-240.5°; $[\alpha]_D +138^\circ$; λ_{max} 222 $\text{m}\mu$ (ϵ 7,700, shoulder), 282-288 $\text{m}\mu$ (ϵ 2,300);

$\lambda_{\text{max}}^{\text{KBr}}$ 3.00 μ , 3.45 μ , 6.30 μ , 6.74 μ , 6.87 μ , etc.

Analysis.—Calcd. for $\text{C}_{21}\text{H}_{28}\text{O}_3$: C, 76.79; H, 8.59. Found: C, 76.82; H, 8.52.

Thin-layer chromatography using silica gel chromatoplates developed with hexane-ethyl acetate (4:1) and (1:1) will show a single spot at R_F 0.17 and 0.74 respectively, positive (bluish-violet) to phosphomolybdic acid. 1-hydroxy-4-methylestra-1,3,5(10)-trien-17-one has R_F 0.12 and 0.72 respectively.

EXAMPLE 2

17,17-Ethylenedioxy-1-Methoxy-4-Methylestra-1,3,5(10)-Triene

Treat a solution of 500 mg. of 17,17-ethylenedioxy-4-methylestra-1,3,5(10)-trien-1-ol in 75 ml. of boiling methanol with 175 ml. of 10% aqueous sodium hydroxide

solution dropwise. Then add 25 ml. of dimethyl sulfate dropwise over a 20-minute period. Add a second 175 ml. portion of sodium hydroxide solution and a second 25 ml. portion of dimethyl sulfate, keeping the solution at boiling point during the several additions. Cool the mixture, and dilute with 200 ml. of water. Filter the precipitated product and dry in air.

EXAMPLE 3

1-Ethoxy-17,17-Ethylenedioxy-4-Methylestra-1,3,5(10)-Triene

Treat a solution of 500 mg. of 17,17-ethylenedioxy-4-methylestra-1,3,5(10)-trien-1-ol in 25 ml. of absolute ethanol with 5 ml. of ethyl bromide and 300 mg. of sodium hydroxide. Reflux the mixture for 15 hours, then evaporate the solvent under vacuum. Dissolve the residue in carbon tetrachloride and wash the solution with 5% sodium hydroxide solution, then with water. The carbon tetrachloride is then removed under vacuum, and the solid residue is crystallized from acetone.

EXAMPLE 4

1-Cyclopentyloxy-17,17-Ethylenedioxy-4-Methylestra-1,3,5(10)-Triene

Reflux a mixture of 500 mg. of 17,17-ethylenedioxy-4-methylestra-1,3,5(10)-trien-1-ol, 15 ml. of cyclopentyl bromide, 15 ml. of absolute ethanol, and 500 mg. of sodium hydroxide for twenty hours. Remove the solvents under vacuum and take up the solid residue in carbon tetrachloride. Wash the carbon tetrachloride solution with 5% sodium hydroxide solution and then with water. After drying the carbon tetrachloride solution over anhydrous magnesium sulfate, remove the solvent under vacuum. Dissolve the solid product in acetone, concentrate slightly, and cool. Filter off the precipitated crystalline product.

EXAMPLE 5

1-Allyloxy-17,17-Ethylenedioxy-4-Methylestra-1,3,5(10)-Triene

Treat 500 mg. of 17,17-ethylenedioxy-4-methylestra-1,3,5(10)-trien-1-ol with 15 ml. of ethanol, 5 ml. of allyl bromide and 100 mg. of sodium hydroxide. Reflux the mixture for 18 hours, after which time remove the organic solvents under vacuum. Dissolve the solid residue in carbon tetrachloride, and wash the carbon tetrachloride solution with 5% sodium hydroxide solution and then with water. The carbon tetrachloride may then be removed under vacuum and the solid product dissolved in methanol. Concentrate the methanol solution until crystallization begins, then refrigerate to complete the precipitation of product. The crystalline product is then recovered by filtration.

EXAMPLE 6

1-Benzylxy-17,17-Ethylenedioxy-4-Methylestra-1,3,5(10)-Triene

Reflux a mixture of 500 mg. of 17,17-ethylenedioxy-4-methylestra-1,3,5(10)-trien-1-ol, 25 ml. of ethanol, 5 ml. of benzyl bromide, and 200 mg. of sodium hydroxide for 15 hours. Remove the solvents under vacuum and take up the solid residue in carbon tetrachloride. Wash the carbon tetrachloride solution with 5% sodium hydroxide solution and then with water. Dry the carbon tetrachloride solution over anhydrous magnesium sulfate and remove the solvent under vacuum. The solid product may be dissolved in methanol, concentrated a bit, and cooled to cause precipitation of crystalline product.

EXAMPLE 7

1-Acetoxy-17,17-Ethylenedioxy-4-Methylestra-1,3,5(10)-Triene

First dissolve 100 mg. of 17,17-ethylenedioxy-4-methylestra-1,3,5(10)-trien-1-ol in 10 ml. of dry pyridine and

add 3 ml. of acetic anhydride. After keeping at room temperature for 18 hours, evaporate the solvents under vacuum and dissolve the residual amorphous product in acetone. While boiling the solution add hexane until crystallization commences. Cool the solution and filter the crystalline product.

EXAMPLE 8

4-Methyl-17,17-Trimethylenedioxyestra-1,3,5(10)-Trien-1-Ol

Reflux a mixture of 100 mg. of 1-hydroxy-4-methylestra-1,3,5(10)-trien-17-one, 25 ml. of benzene, 100 mg. of p-toluenesulfonic acid and 5 ml. of 1,3-propanediol for twenty hours. Cool the mixture, wash with saturated sodium bicarbonate solution and then with water. Dry the benzene solution over anhydrous magnesium sulfate and evaporate the solvent under vacuum. The solid residue may be dissolved in acetone and the solution concentrated until crystallization commences, at which time a small amount of hexane may be added. Leave standing for several hours, and then filter and dry the crystalline product.

EXAMPLE 9

17,17-Ethylenedithio-4-Methylestra-1,3,5(10)-Trien-1-Ol

Cool a mixture of 500 mg. of 1-hydroxy-4-methylestra-1,3,5(10)-trien-17-one, 3 ml. of ethanedithiol, and 20 ml. of chloroform to 5° and bubble anhydrous hydrogen chloride through the solution for three hours. Then remove the solvent under vacuum and take up the residual gum in warm acetone. Concentrate the acetone solution somewhat and add hexane. The crystalline product crystallizes and may be recovered by filtration.

EXAMPLE 10

17,17-Ethylenethioxy-4-Methylestra-1,3,5(10)-Trien-1-Ol

Reflux a solution containing 500 mg. of 1-hydroxy-4-methylestra-1,3,5(10)-trien-17-one, 30 mg. of p-toluenesulfonic acid in 75 ml. of dry benzene containing 2 ml. of 2-mercaptoethanol. After six hours of reflux cool the mixture and wash it with saturated sodium bicarbonate solution and then with water. Evaporate the benzene solution and dissolve the residue in methanol. Concentrate the methanol solution until crystallization begins and then cool to cause complete precipitation of the crystalline product.

We claim:

1. A compound of the structural formula:

wherein R represents a substituent selected from the group consisting of hydrogen, lower alkyl, lower alkenyl, lower cycloalkyl of up to 6 carbon atoms, lower aralkyl, and lower alkanoyl; R' represents a lower alkyl group; and W represents a member selected from the group consisting of lower alkylmethoxymethylene of up to 4 carbon atoms, lower alkylmethioxymethylene of up to 4 carbon atoms, and lower alkylmethiodithiomethylene of up to 4 carbon atoms.

2. A compound according to claim 1 wherein R represents hydrogen, R' represents lower alkyl and W represents lower alkylmethoxymethylene of up to 4 carbon atoms.

25 3. 17,17-ethylenedioxy-4-methylestra-1,3,5(10)-trien-1-ol.

4. 17,17-ethylenedioxy-1-methoxy-4-methylestra-1,3,5(10)-triene.

5. 1-ethoxy-17,17-ethylenedioxy-4-methylestra-1,3,5(10)-triene.

30 6. 1-allyloxy-17,17-ethylenedioxy-4-methylestra-1,3,5(10)-triene.

7. 1-benzyloxy-17,17-ethylenedioxy-4-methylestra-1,3,5(10)-triene.

35 8. 4-methyl-17,17-trimethylenedioxyestra-1,3,5(10)-trien-1-ol.

9. 17,17-ethylenedithio-4-methylestra-1,3,5(10)-trien-1-ol.

10. 17,17-ethylenethioxy-4-methylestra-1,3,5(10)-trien-1-ol.

11. 1-acetoxy-17,17-ethylenedioxy-4-methylestra-1,3,5(10)-triene.
